UNITED STATES PATENT OFFICE.

FRED COLLEY, OF AKRON, OHIO, ASSIGNOR TO THE GOODYEAR TIRE & RUBBER COMPANY, OF AKRON, OHIO, A CORPORATION OF OHIO.

BALE-TEARING MACHINE.

Application filed March 31, 1925. Serial No. 19,748.

My invention pertains to rubber manufacture and it is particularly related to the manipulation of crude baled rubber.

One object of my invention is to provide 5 a machine for separating baled rubber into sections of such size as to facilitate manipulation of the rubber on an ordinary mill.

Another object of my invention is to provide 10 a machine which will minimize the manual labor heretofore required, as well as to eliminate the disagreeable character of the work.

Baled crude rubber, as received from 15 plantations, is made up of a plurality of sheets, each being approximately twelve inches wide, from twenty-four to thirty inches long and less than a quarter of an inch thick. Several such sheets are superposed to form what may be called a book.

20 This unit is approximately two and one-half inches thick and about fifteen inches square.

A plurality of books, in turn, are compressed to form a bale, which contains approximately 240 pounds of rubber.

25 It is commonly known that plastic materials may be made integral with each other under the action of pressure and heat. This phenomenon is present in the handling of raw rubber and is met only at considerable expense, since a bale must be separated 30 into book form before the rubber can be utilized in any manufacturing process. In the past this separation has been accomplished manually. The work is not only 35 disagreeable but strenuous, especially in cases where the bale has aged, thereby causing adjacent elements to unite in forming a substantially inseparable union. At best, it is only with considerable exertion that one

40 is able to manipulate these large masses of rubber in order to dislodge the subordinate units. To overcome this undesirable task, I have provided a machine which will clamp a bale in position and disengage the individual units.

45 In the accompanying drawings:

Fig. 1 is a side view of a machine embodying my invention and

Fig. 2 is an end view thereof.

50 Referring to Fig. 1, it will be apparent that the clamping means and the disengaging device are separate units which, however, operate in conjunction to effect a common purpose. The clamping device consists of a frame having two horizontally

disposed base members 3, to each of which are joined vertical standards 4, which are held in position by braces 5 and cross members 6. The base members are maintained in parallel relationship by means of angle irons 7, which also serve as supports for other angle irons 8, parallel to and above the base members 3. Irons 8 journal a plurality of rolls 9 which are adapted to convey bales of rubber to a final position, indicated by broken lines at 10.

In the position indicated, the bales rest on a plurality of sharpened prongs 12, vertically disposed upon supplementary channel irons 13, which are rigidly connected to the frame by a cover plate 14 and bolts 15. The bale is made secure in the device by additional prongs 18, formed integrally with a clamping member 17, which is adapted for reciprocating movement between guides 19. The member 17 is linked to a connecting rod 20 that is actuated by a piston in a cylinder 22. A pivotal joint 23 allows for horizontal play of member 17 on its guides without disturbing the actuating mechanism.

70 The piston within the cylinder is actuated by a pressure fluid which is admitted through a two-way valve 24 from a source of supply, not shown. In operating the piston, when air, for example, is admitted to the base of the cylinder through a conduit 26, the air above the piston is allowed to exhaust to the atmosphere through a conduit 27. By reversing the valve position, air 75 may be admitted through the pipe 27, thus forcing the piston downward and at the same time allowing the fluid below the cylinder to exhaust through the pipe 26.

80 The disengaging means is suspended from an overhead support 30 and comprises a cylinder 31 provided with a control valve 32, which is similar to the valve 24. A rod 33 connects a piston within the cylinder to a chain 34 carrying a hook 35. By forcing the valve handle downward, as indicated by the arrow, a fluid under pressure, preferably air, is admitted to the base of the cylinder 85 which causes the rod and chain to move upwardly. Upon releasing the valve handle, a spring 36 actuates the valve to reverse the direction of flow of the air and the piston drops to its original position.

105 The operation of the machine will be apparent from the foregoing description. A bale of rubber to be separated into its sub-

ordinate units is readily disposed in position by moving it over the rollers 9 into position under the clamping member 17, which is initially in raised position. Air is then admitted to the cylinder 22 by operation of the valve 24, effecting a downward movement of the piston contained in the cylinder to cause engagement of the member 17 with the bale of rubber. Thereafter, the hook 35 is lowered to a suitable position by operation of the valve 32, and the hook is then engaged with a portion of the bale. Thereupon the valve 32 is again operated in a reverse direction to effect an upward movement of the hook 35, whereby a portion of the rubber engaged by the hook is separated from the main body portion of the bale. The operation of lowering and raising the hook is repeated the requisite number of times to separate the bale into the number of units desired. The clamping member 17 is then raised from engagement with the bale by suitable operation of the valve 24 to direct air into the lower part of the cylinder 22 through the conduit 26.

It will be realized that by practicing my invention, the bales may be reduced with a minimum of manual labor. Moreover, the work is no longer disagreeable, inasmuch as no heavy units need be handled.

Although I have described and illustrated but a single embodiment of my invention, it will be apparent to anyone skilled in the art that it is not so limited and may be subjected to wide variations without departing from the spirit and scope thereof. I desire, therefore, that only such limitations shall be imposed as are consistent with the appended claims.

What I claim is:

1. A machine for tearing bales which comprises a frame provided with means for conveying a bale to an operable position, and means for engaging a portion thereof while separating its composite units. 40

2. A machine for tearing bales of rubber which comprises a frame provided with a means of approach, a pneumatically controlled means for clamping the bale and means for separating its composite units. 45

3. A rubber bale tearing machine comprising a frame, fluid-controlled means for securing a bale of rubber mounted therein and fluid-controlled means for disengaging the units of the rubber bale. 50

4. A bale tearing machine including means for disengaging the units of a bale, means adapted to convey the bale to a clamping device, said device comprising a pressure fluid mechanism adapted to compress the bale between irregular surfaces. 55

5. A bale tearing machine comprising a frame provided with a clamping device, a suitable conveyor and manually controlled means adapted to detach single leaves comprising a hook joined to a reciprocating mechanism. 65

6. A bale separating machine comprising a frame, a pneumatically operated clamping member mounted for reciprocating movement in the frame, a plurality of rolls forming an approach to the clamping member and a hook juxtaposed to the clamping member and flexibly connected to a pneumatically operated piston. 70

In witness whereof, I have hereunto signed my name.

FRED COLLEY
